INTERLOCKING DEVICE

George G. Keyes, Chicago, Ill., assignor to Tele-type Corporation, Chicago, Ill., a corporation of Delaware

Application July 2, 1945, Serial No. 602,714

6 Claims. (Cl. 178—17)

1

The present invention relates to telegraph apparatus and more particularly to record strip controlled transmitting devices and interlocking record strip cooperating devices therefor.

In telegraph systems comprising a central station and a plurality of local stations utilizing tape transmitters, it is desirable to have identification codes recorded in the tape preceding the message to inform the central station as to where the message originated. The identification code designations for the local stations are made up of a group of signals arranged in predetermined sequences peculiar to each station. Therefore, to insure proper station identification, it is imperative that the transmission of the message from the local station begins with the first signal of the station identification code.

Thus, the principal object of this invention is to provide a device for withdrawing the tape feeding means out of engagement with the feed perforations of the record tape and locking said means in its withdrawn position to enable the operator to manually feed the tape to any desired position in relation with the sensing pins. For instance, to position the tape in such a manner that when the transmitter is started, the first signal of the station identification code will be the first signal transmitted.

Another object of this invention is to provide means for locking the tape-out control contact pair in an opened position after it has been opened by the tape-out sensing pin, whereby said means is adapted to be restored to its unoperated position by manual means.

A feature of this invention is the utilization of the aforementioned manual means to unlock the tape feed withdrawing means so that the tape feeding mechanism may engage the feed perforations in the tape. This feature will be set forth more fully hereinafter in the detailed description of operation.

In general, the apparatus comprises a mounting bracket secured to the base casting of a printing telegraph apparatus of the type disclosed in U. S. Patent No. 2,355,657, issued on August 15, 1944, to R. A. Lake, upon which are mounted pivotally the tape-out locking lever and the tape feed withdrawing lever. The extremity of the tape-out locking lever is bent at a right angle and has a projection thereon which cooperates with an insulated extension of a spring of the contact pair connected in series with the transmitter clutch electromagnet. The tape-out locking lever is normally held out of engagement with the spring of the contact pair by means of

2

a shoulder on a pivoted lever secured to the aforementioned bracket at a right angle to the tape-out locking lever. The pivoted lever has a projection which cooperates with an extension of a depending finger of the tape-out pin cam follower.

When there is no tape in the transmitter, the sixth pin (tape-out pin) is allowed to move upwardly through its associated aperture in the tape guideway, thereby its associated cam follower is rotated counterclockwise as it reaches the low portion of its associated cam. Thus, the extension of the depending finger of said cam follower is moved forward to open the contact pair to break the transmitter clutch magnet circuit, thereby rendering the transmitter unoperative. As the extension of the depending finger is moved forward it also rotates the pivoted lever which is blocking the tape-out locking lever so that the tape-out locking lever may be rotated counterclockwise under the urging of its associated spring to cause the projection at its extremity to lock the contact pair in its open position.

25 After another tape is inserted in the transmitter, the operator depresses the tape-out locking lever, rotating it in a clockwise direction until the pivoted lever is again blocking the tape-out locking lever from engaging the contact pair, thereby allowing said contact pair to close and be under the influence of the tape-out pin.

Also provided in the device is a tape release lever which lowers the tape feed arm out of engagement with the feed perforations in the tape so that the operator may manually feed the tape through the transmitter to any desired position.

When the operator depresses the tape release lever, it is rotated in a clockwise direction. Thereby its extremity engages a camming surface of a depending finger of the tape feed cam follower to rotate it in a clockwise direction, lowering the tape feed arm out of engagement with the feed perforations in the tape. A bell crank mounted pivotally on the bracket, at a right angle to the tape release lever, has a shoulder at the extremity of its vertical arm which engages the tape release lever to lock it in its operative position.

After the tape is positioned, the operator depresses the tape-out locking lever. The tape-out locking lever rotates in a clockwise direction and raises an extended portion of a second arm of the bell crank to rotate said bell crank in a counterclockwise direction so that the shoulder of the vertical arm is no longer blocking the tape

release lever. The tape release lever is then returned to its unoperative position by the urging of its associated spring, thereby allowing the tape feed arm to engage the feed perforations in the tape.

A more complete understanding of the foregoing and other objects and features of the present invention may be had from the following description when taken in conjunction with the accompanying drawing, wherein like reference characters designate similar parts throughout the several views, and in which

Fig. 1 is a partial front sectional view of that portion of the printing telegraph apparatus disclosed in the aforementioned patent, necessary to describe the present invention which is incorporated therein;

Fig. 2 is a sectional view taken substantially on lines 2—2 of Fig. 1, and

Fig. 3 is a perspective view of the apparatus embodying the present invention.

Briefly, the structure of the aforementioned Lake patent, which exemplifies a device to which the present invention is adapted, may be considered as including three principal units; namely a printing reperforator 11, a tape sensing unit 12, and a transmitting unit (not shown). Each of the several units is mounted on base casting 13.

The printing reperforator 11, included in the apparatus under consideration, is substantially the same as that printing reperforator disclosed in the aforementioned Lake Patent No. 2,355,657 and for a more complete understanding of the structure and mode of operation of this unit, reference may be had to said patent which is incorporated herein by reference.

A punch block 14, Fig. 1, secured to the reperforator casting 15 is suitably apertured to receive in a slidable manner the code punches 16 which project through the punch block 14 and a guide comb 17. Interponents or permutation elements 19 are movable back and forth over the face of cradle 18 and are adapted to be positioned in different combinations to place the outer ends thereof, either in operative positions beneath the corresponding punches 16, or in unoperative positions out of alignment with punches 16.

Upon each permutative setting of the interponents 19, cradle 18 is rocked in a clockwise direction to produce a row of perforations in the tape 21 through the actuations of punches 16 corresponding to the setting of the interponents 19. The punches 16 are flattened or hammered out at their lower extremities to provide suitable shoulders beneath a comb 17 so that as cradle 18 is rocked in a counterclockwise direction, comb 17 may withdraw punches 16 to their lowermost positions. A feed sprocket 22 is provided to cooperate with the feed holes in the tape 21, and is effective through well known pawl and ratchet devices to step the tape through the punch block 14.

The sensing unit 12 employed with the printing reperforator is of the pivoted or traveling type which is adapted to sense every code perforation recorded in a tape by the printing reperforator without the necessity of stepping the perforated tape a plurality of feeding distance from the perforating unit into the sensing unit. This sensing unit, as shown in Figs. 1 and 2, is substantially the same as the sensing unit shown in the aforementioned Lake patent with the exception that the rectilinear feeding mechanism has been changed to conform with the feeding mechanism disclosed in copending application Serial No. 75

521,315, filed February 7, 1944, now Patent No. 2,388,965 of November 13, 1945, by M. T. Goetz. The sensing unit comprises essentially a plurality of sensing elements to sense the perforations in a tape, a member for feeding the tape through the sensing unit having imparted to it rectilinear motion, and a cam drum for controlling the operation of the sensing elements and the tape feeding member.

10 Unit 12 has a base casting 23, Figs. 1 and 2, which is removably mounted upon the base casting 13 of the apparatus. The casting 23 consists of a pair of parallel vertical wall sections 24 interconnected by a relatively flat web portion 25. The leftward extremity of portion 25 is formed into a vertical portion which is channeled to serve as a journal for a shaft 26 and slotted to provide a comb which serves to guide the vertical oscillations of the members which support and operate the sensing elements. The rightward portion of wall sections 24 support pivot studs 27 upon which the movable or pivoted portion of the sensing unit is secured. Specifically, the frame members 28 and 29 are secured to the pivots 27. A plate 31 is carried by the pivoted frame members and carries a hinge post 32 upon which is hingedly supported a tape gate 33 which in conjunction with the plate 31 defines the passageway for the perforated tape 21 through the sensing unit. A spring latch 34, Fig. 2, secured to a bracket 35 mounted on frame member 29, holds the tape gate 33 in cooperating relation with the plate 31.

As viewed in Fig. 2, plate 31 is provided with a plurality of apertures to receive the reduced portion or end of a corresponding series of sensing pins 36; that is, there is a sensing pin 36 individual to each of the code apertures adjacent to the edge of plate 31. Inasmuch as a five unit code is utilized, there will be a corresponding number of sensing pins 36, for example, there will be a sensing finger or pin 36 for each of the possible code perforations appearing in a transverse row of perforations.

The rectilinear feed means, as shown in Figs. 1 and 2, is comparable in action to that disclosed in the aforementioned R. A. Lake patent, but instead of the pin and cam slot arrangement of the latter patent, a rectilinear feed means is provided which is comparable to the rectilinear feed means disclosed in the above-identified patent No. 2,388,965.

Intermediate the upper portions of the frame members 28 and 29 and in the space determined by the spacer 37 is a slidably movable member 38 which carries on its upper extremity a plurality of tape feed pins 39. Pins 39 are so spaced as to engage four successive feed holes in the tape 21. The purpose of providing feed pins for simultaneously engaging four feed holes in the tape is to minimize the possibility of the feed perforations becoming mutilated. A pin or wedging element 41 is carried on a lever 42 and is reciprocated vertically during the tape feeding operation. The pin 41 cooperates with surface 43 of spacer 37 and surface 44 of member 38.

The member or spacer 37 has two operating surfaces 43 and 45. In addition, member 37 functions to space the upper portions of the frame members 28 and 29 apart to form a guide for the arm 38. The surface 45 of spacer 37 cooperates with the right-hand upper edge of arm 38 to form the right-hand limit stop for feed pin arm 38. Arm 38 is biased toward this stop surface 45 at all times by springs 46, Fig. 1, only one of which 70 is shown. The upper left-hand edge of the tape

feed arm 38 indicated at 47 cooperates with an adjustable stop 48 as the pin 41 on the arm 42 is reciprocated downwardly, as will presently appear.

As will be described hereinafter, arms 38 and 42 are operated in timed relation with each other. Arm 42 is drawn downwardly, and when so drawn, and due to the particular inter-relation between the surfaces 43 and 44, member 38 will be moved to the left to effect relative movement between the sensing unit 12 and the tape 21. Member 38 then is moved downwardly to withdraw the tape feed pins 39 from engagement with the feed perforations in the tape 21. As arm 38 is thus moved downwardly, arm 42 is also moved downwardly simultaneously an additional amount to maintain arm 38 against stop 48, thereby insuring the downward movement or withdrawal of the tape feed pins in a straight line. Following this action, arm 42 is moved upwardly, and due to the cooperation between surfaces 43 and 44 and springs 46, member 38 is moved to the right to engage the stop surface 45 of member 37. The member 38 is thereafter elevated to cause the pins 39 to engage other feed perforations in the tape 21 to achieve, on a subsequent cycle, relative movement between the sensing unit 12 and the tape 21.

On the shaft 26 which is supported by the channel formed in the leftward portion of base casting 23 of the sensing unit are supported pivotally a plurality of Y-levers 49 as well as other levers including those required to control the operation of the members 38 and 42 of the tape feeding mechanism. The Y-levers 49 are individual to the sensing fingers 36 and those fingers are secured pivotally to the arms of the Y-levers 49 extending to the right of the shaft 26 as seen in Fig. 1. The leftward portions of the Y-levers 49 extend through a guide comb 51 which is secured to the vertical walls of the base casting 23 of the sensing unit 12. The comb is suitably slotted to guide the vertical operation of the Y-levers 49 about the shaft 26. Each Y-lever 49 is provided leftwardly of the shaft 26 with an upstanding projection 52 to which is secured a spring 53, the other end of which is secured to a member 54, mounted on the guide comb 51. Springs 53 tend normally to rotate the Y-levers 49 in a counterclockwise direction about shaft 26 so that projections 55 on the lower leftward extensions of Y-levers 49 cooperate with the peripheries of cams 56 to reciprocate the sensing fingers 36 vertically to sense the perforations in the tape 21 in a manner to be described hereinafter.

As may be seen in Fig. 2, two additional sensing pins 73 and 74 are provided which press each edge of the tape 21 against the tape gate 33 to hold the tape against movement when the member 38 is out of engagement with the feed perforations of the tape 21. The sensing pins 73 and 74 are secured to cam controlled Y-levers 49 in a manner similar to the manner in which the aforementioned code sensing pins 36 are secured to their associated Y-levers 49. The purpose of the pins 73 and 74 will be more clearly understood in the operational description to be set forth hereinafter.

The sensing pin 74 has a double function, primarily to be utilized as afore-mentioned, and also as a tape-out control. The Y-lever 49 which controls the sensing pin 74 has a depending arm 75 which has a cylindrical blocking member 76 secured thereto. When there is no tape in the sensing unit, the sensing pin 74 is permitted to

be raised to its uppermost position by its associated Y-lever 49, thereby causing the member 76, secured to depending arm 75, to move the spring 77 of contact pair 78 to the right, Fig. 1, thereby opening contact 78 to break the sensing unit control circuit, which will hereinafter be described.

Also supported pivotally by shaft 26 is a bell crank lever 57, Figs. 1 and 2, which has secured pivotally to its extremity the member 38. Extending to the right from the rearward portion of the U-shaped portion 58 of the bell crank lever 57 is an upstanding projection 59 to which is secured a spring 61 which normally tends to bias the crank lever 57 in a counterclockwise direction about shaft 26. A cam follower 62, which cooperates with the periphery of cam 64, is also mounted pivotally on shaft 26 and is secured to the projection 59 of the bell crank lever 57 by means of a screw 63. Thus, it may be seen that the vertical reciprocation of the member 38 is controlled by the configuration of cam 64.

The lever 42 which carries the pin 41 is pivotally secured to the rightward extremity of a bell crank lever 65 which is supported pivotally on shaft 26. Bell crank lever 65, Figs. 1 and 2, is secured to an upstanding projection 66 of a lever 67 by means of a screw 68. A spring 69, shown in dotted lines in Fig. 1, is secured to a horizontal extension of the lever 67 to normally bias it in a clockwise direction so that the roller 71, Figs. 1 and 2, will cooperate with the periphery of its associated cam 72 to impart vertical reciprocation to the lever 42.

All of the afore-mentioned cams are mounted on a cam drum 79, Figs. 1 and 2, which is supported on a constantly rotating shaft 81. The rotation of the cam drum 79 is controlled by a grab clutch (not shown) of a type which is well known in the art and is described in detail in the aforementioned R. A. Lake patent. The clutch is operated by an electromagnet (not shown) in such a manner that when the electromagnet remains energized the cam drum 79 will rotate continuously, and upon de-energization of the electromagnet the clutch is disengaged after cam drum 79 completes its instant cycle of revolution.

The energization of the electromagnet is under the joint control of a manually operated switch (not shown), a transmitter operated switch, and the tape-out contact pair 78, all of which are connected in series. The transmitter operated switch (not shown) is controlled by means of a rightwardly extending projection 82 (comparable to projection 206 of Lake Patent 2,355,657) of frame member 28. When the sensing unit 12 in pivoting about its pivots 27 has reached its ultimate clockwise position, projection 82 will operate the switch to break the circuit of the transmitter clutch magnet and arrest the operation of the cam sleeve 79. Thus, it may be seen that the operation of the sensing unit 12 may be initiated when desired by the manual switch and terminated automatically upon the operation of the sensing unit as it senses the last code signal combination perforated in the tape by the printing reperforator 11, or upon the absence of a tape in the sensing unit, as previously described.

A mounting bracket 83, Figs. 2 and 3, is secured to the base casting 13 by means of screws 84. A lever 85 having a shoulder 86 is mounted pivotally on the bracket 83 by means of stud 87 and normally tends to rotate in a clockwise

direction under the urging of expansion spring 88, Fig. 3. Also mounted pivotally on the bracket 83 by means of stud 89 is the tape-out control locking lever 91, shown in Figs. 1, 2, and 3, with only that portion of lever 91 which cooperates with the tape-out contact pair 78 shown in Fig. 1. The rightward portion of lever 91, Fig. 3, forms a vertical arm 92 and terminates in a finger piece 93. The leftward extremity of lever 91 is offset and terminates in a projection 94. The lever 91 is urged in a counterclockwise direction by means of spring 95 and cooperates with the shoulder 86 on lever 85.

Located directly above stud 87 on lever 85 is a projection 96, Fig. 3, which cooperates with the blocking member 76, as shown in Fig. 1. When the blocking member 76 is moved to the right (Fig. 1), it urges both the spring 77 of contact pair 78 and the projection 96 rightwardly. Thus, the shoulder 86 of lever 85, Fig. 3, is removed from blocking engagement with the lever 91 which, due to the pull of its associated spring 95, is rotated in a counterclockwise direction causing projection 94, Fig. 1, to latch the contact spring 77 in its rightward position, thereby holding the contact 78 open.

Mounted pivotally on bracket 83 by means of a stud 97 is the tape release lever 98, Figs. 1, 2, and 3, with only that portion of lever 98 which cooperates with the depending arm 99 of cam follower 62 shown in Fig. 1. The rightward portion of lever 98, Fig. 3, forms a vertical arm 101 and terminates in a finger piece 102. The tape release lever 98 is normally urged in a counterclockwise direction by spring 103, Fig. 3.

When the lever 98 is rotated in a clockwise direction, its leftward extremity, Fig. 3, cooperates with the camming surface 108 (Fig. 1) to rotate depending arm 99 of cam follower 62 in a clockwise direction, Fig. 1, thereby moving the member 38 downwardly so that feed pins 39 are lowered out of engagement with the feed perforations of tape 21.

Also mounted pivotally on bracket 83, by a stud 107, is a bell crank lever 104 which normally tends to rotate in a counterclockwise direction under the urging of the expansion spring 88. The vertical arm 105 of the bell crank lever 104 has a shoulder 106 thereon which latches the lever 98 in its clockwise position (Fig. 3). An arm 108 of the bell crank lever 104 has its extremity disposed directly above and in the path of lever 91, so that the clockwise rotation of lever 91 (Fig. 3) will raise the arm 108, thereby rotating the bell crank lever 104 sufficiently to move the shoulder 106 out of latching engagement with lever 98 to allow it to return to its normal position, Fig. 3.

A brief description of the operation of the sensing unit will now be given to illustrate more clearly the manner in which the present invention is utilized in conjunction with the sensing unit.

Assuming the printing reperforator 11 to be operating at a greater speed than the sensing unit 12, a loop of tape will be formed intermediate the units 11 and 12, and the sensing unit 12 will pivot on studs 27 in a counterclockwise direction (Fig. 1) until the adjustable stop 109 is reached. As the cam drum 79 is rotated, Fig. 1, pin 41 is actuated downwardly to move the member 38 to the left until it reaches the stop 48, thereby moving the tape 21 into position for the first transverse row of code perforations to be sensed by the sensing pins 36. As cam drum 79 continues to

rotate, cams 56 simultaneously present cam depressions to the plurality of Y-levers 49 to elevate the sensing pins 36 into tape probing position under the influence of biasing springs 53 individual to each Y-lever. The member 38, now in its leftward position, is lowered in timed relation with pin 41, as clearly shown in the co-pending M. T. Goetz application, so that the feed pins 39 are disengaged from the feed perforations in tape 21. The sensing pins 73 and 74 are operated at the same time as the sensing pins 36 and press the edges of the tape 21 against the tape gate 33, thereby holding the tape in a fixed position while the member 38, in its lowermost position is moved rightwardly till it reaches the stop 45. As the cam drum 79 reaches the end of its revolution, the member 38, in its rightward position against stop 45, is raised to its uppermost position with the feed pins 39 in engagement with the feed perforations of tape 21 and the sensing pins 36, 73 and 74 are retracted. This operation is repeated cyclically as the tape is passed through the sensing unit 12.

When the tape in the sensing unit 12 has become depleted or broken, or in response to a special perforation in the rightward edge of the tape as viewed in Fig. 2, the sensing pin 74 is permitted to be raised to its uppermost position by its associated Y-lever 49, thereby causing the member 76 (Fig. 1), secured to depending arm 75, to move the spring 77 of contact pair 78 to the right, to break the circuit of the aforementioned clutch electromagnet, thus stopping the operation of the sensing unit. The projection 96 of the lever 85 is also moved to the right by member 76 (leftwardly as viewed in Fig. 3), thereby allowing the lever 91 to drop off of shoulder 86 of lever 85, Fig. 3, allowing the projection 94 of lever 91, Fig. 1, to latch the contact spring 77, thus preventing contact pair 78 from closing until the operator manually resets lever 91.

After a new tape has been inserted in the sensing unit, the operator depresses the finger piece 102 of the lever 98. The extremity of the lever 98, Fig. 1, thereby cooperates with the camming surface 108 of the depending finger 99 to lower the member 38. The bell crank lever 104, Fig. 3, is rotated counterclockwise under the urging of spring 88 so that the shoulder 106 of the bell crank lever 104 blocks the lever 98 from returning to its normal position. Thus, the feed pins 39, Fig. 1, are held disengaged from the feed perforations of the tape to enable the operator to adjust the tape manually so that the sensing unit may resume transmission with any desired transverse row of code perforations aligned with the sensing pins. A stop 111, Fig. 3, is provided so that the rotation of lever 98 may be limited to an amount sufficient to achieve the desired results.

When it is desired to resume transmission, the operator depresses the finger piece 93 of lever 91, thereby raising the projection 94 of lever 91, Fig. 1, out of latching relation with contact spring 77 so that contact pair 78 may be closed to permit the re-energization of the clutch magnet thus allowing the sensing unit to resume operation. As the lever 91, Fig. 3, is rotated clockwise it engages the arm 110 of the bell crank lever 104, rotating it in a clockwise direction so that the shoulder 106 of vertical arm 105 is withdrawn from latching engagement with the tape release lever 98. The lever 98 is thereby permitted to rotate in a counterclockwise direction under the pull of the spring 103 to its normal

position to allow the member 38 to elevate so that the feed pins 39 engage the feed perforations of the tape. When the operator releases finger piece 93, the lever 91, under the pull of the spring 95, is rotated in a counterclockwise direction until it is again resting on the shoulder 86 of the lever 85.

A further purpose of the shoulder 86 is to preclude the operator from raising the finger piece 93, thereby rotating the lever 91 in a counterclockwise direction (Fig. 3) and causing the projection 94 (Fig. 1) to mutilate the contact pair 78. A stop 112, located at the upper extremity of lever 85 is provided to prevent the operator from rotating the lever 91 more than is necessary.

Although a specific embodiment of the invention has been disclosed in the drawings and described in the specification, it is to be understood that the invention is not limited to such specific embodiment but may be modified and rearranged without departing from the spirit and scope of the invention.

What is claimed is:

1. In combination, a record reader including means for sensing indicia in a record strip, a record strip feeding means, automatic means for operating said feeding means, an interlocking device comprising a manually operated means for rendering said automatic means ineffective and locking means therefor, means responsive to a condition of record strip depletion for arresting the operation of said sensing means, said interlocking device including means for locking said arresting means, and further manually operated unlocking means included in said interlocking device dually effective for enabling the re-operation of said automatic means and initiating the operation of said sensing means.

2. In a record reader, a strip feeding device comprising a fixed member having a wedging surface, cam means, a movable strip feeding member having a wedging surface, said feeding member controlled by said cam means, a wedging element cooperable with said wedging surfaces and operated by said cam means in timed relation with said feeding member to impart step by step movement to a record strip, a depending arm having a camming surface thereon, and a manually operated element cooperating with the camming surface of said depending arm to withdraw said feeding member out of engagement with the feed holes in said record strip independently of said cam means.

3. In combination, a record reader including means for sensing indicia in a record strip, control means, means effective under a certain condition of operation of said sensing means indicative of record strip depletion to operate said control means, a strip feeding device including a fixed member having a wedging surface, cam means, a movable feeding member having a wedging surface, said feeding member controlled by said cam means, a wedging element cooperable with said wedging surfaces and operated by said cam means in timed relation with said feeding member to impart step by step movement to said record strip, a depending arm having a camming surface thereon, a manually operated element effective to cooperate with the camming surface of said depending arm to withdraw said feeding member out of engagement with the feed holes in said record strip independently of said cam

means, means for locking said manually operated element in its operative position, and manually operated means for unlocking said manually operated element and said control means to render said control means responsive to the further control of said sensing means.

4. In combination, a record reader including means for sensing indicia in a record strip, control means, cam means, said cam means timing the operation of said control means, record strip feeding means effective under the control of said cam means to impart step by step movement to said record strip, means effective under a certain condition of operation of said record reader indicative of record strip depletion to operate, through the instrumentality of said cam means, said control means to govern said record reader; an interlocking device comprising a control means locking element, a manually operated means for withdrawing and locking said feeding means out of engagement with the feed holes in said record strip independently of said cam means, and a manually operated member for releasing said control means locking element and said manually operated means.

5. In combination, a record reader including means for sensing indicia in a record strip, record strip feeding means, automatic means for operating said feeding means, a first manually operated means for withdrawing said feeding means out of engagement with the feed holes in said record strip independently of said automatic means, control means, latch means for said control means, means responsive to a condition of tape depletion for operating said control means, a second manually operated means associated with said control means, and means integral with said latch means and cooperatively related with said first manually operated means, whereby said first manually operated means is effective to simultaneously unlatch said control means and said second manually operated means.

6. In combination in a record reader, record strip feeding means, an interlocking means cooperatively related to said record reader, said interlocking means comprising a pair of manually operable pivoted members, a first spring actuated element coacting with one member of said pair of pivoted members, and a second spring actuated element coacting with both members of said pair of pivoted members, and automatic means effective under a certain condition of operation indicative of tape depletion to operate said first spring actuated element to condition said one member of said pair of pivoted members to establish the arrestment of said operation of said record strip feeding means, whereby upon actuation of the other member of said pair of pivoted members said second spring actuated element is conditioned to respond to the manual actuation of said one member of said pair of pivoted members to enable resumption of operation of said record strip feeding means.
